Primary Examiner — Justin M Jonaitis*Assistant Examiner* — Grace Doyle(74) *Attorney, Agent, or Firm* — CANTOR COLBURN LLP(57) **CLAIM**

The ornamental design for a plant pot with fan, as shown and described.

DESCRIPTION

FIG. 1 is a perspective view of a plant pot with fan, showing our new design;

FIG. 2 is a top view thereof;

FIG. 3 is a bottom view thereof;

FIG. 4 is a front view thereof;

FIG. 5 is a rear view thereof;

FIG. 6 is a side view thereof;

FIG. 7 is another side view thereof; and,

FIG. 8 is another perspective view thereof.

The portions of the plant pot with fan shown in broken line form no part of the claimed design. The broken line showing of a plant and substrate in FIG. 8 is for the purpose of illustrating environmental subject matter and forms no part of the claimed design. The stippling in the drawings represents a contrast in appearance.
